RUDOLF H. KJELLMAN AND GUSTAF L. ANDERSSON, OF STOCKHOLM,
SWEDEN, ASSIGNORS TO AKTIEBOLAGET AUTOMATQEVAR, OF
STOCKHOLM, SWEDEN.

AUTOMATIC FIREARM.

SPECIFICATION forming part of Letters Patent No. 690,739, dated January 7, 1902.

Application filed April 30, 1900. Serial No. 14,880. (No model.)

To all whom it may concern:

Be it known that we, RUDOLF HENRIK KJELLMAN and GUSTAF LEANDER ANDERSSON, subjects of the King of Sweden and Norway, and residents of Stockholm, in the Kingdom of Sweden, have invented certain new and useful Improvements in Automatic Fire-arms, of which the following is a specification.

This invention relates to automatic fire-arms, and is designed mainly for application to those for hand use. The characteristics of this firearm are as follows: It has a recoiling barrel and receiver, the latter being located in the fixed frame. In this receiver is mounted a lever which during the movement of the receiver is caused to turn about its fulcrum owing to the presence in its path of detents or impediments on the fixed frame, the latter being in the form of shoulders, lugs, or projections, between which the lower end of the lever engages. The upper end of said lever enters the breech-bolt, which is located in the receiver and is provided at its bottom with a slot or aperture and actuates the firing-pin in the bolt, so as to cock the pin, and also actuates the bolt itself.

The novelty of the present invention lies in the construction whereby when the breech is closed the said actuating-lever occupies such a position that the breech-bolt may be drawn back or out by hand without disturbing said lever; also, in the mounting of the magazine in the recoiling receiver; also, in the cartridge-lifter being provided with a spring-buffer which when the cartridges are exhausted automatically drives rearward the partially-advanced breech-bolt, so as admit of recharging the magazine without preceding manipulation, and, finally, means are provided for retaining the receiver in place after the recoil until the breech-bolt shall have had time to move rearward to the full extent, when the receiver, being then released by the bolt, is moved forward, as usual, by the recoil-spring.

In the drawings which serve to illustrate the invention, Figures 1, 2, 3, 4, and 5 are sectional elevations of the lock mechanism, showing the parts in different positions. Figs. 6, 7, and 8 are cross-sections taken, respec-

tively, at lines A B, C D, and E F in Fig. 4. Fig. 9 includes two views and shows the operating-lever in side and edge elevation. Fig. 10 represents the cartridge-lifter detached, the three views being respectively a side view, a plan, and an end view. Fig. 11 is a sectional view illustrating the retaining devices for the receiver and the firing-pin, and Fig. 11^a is a detail view of the retaining device for the receiver. Fig. 12 is a sectional view illustrating the locking device for the breech-bolt.

1 designates the barrel of the gun; 2, the receiver; 3, the frame; 4, the breech-bolt; 5, the firing-pin; 6, the spring of the latter; 7, the lever; 8, the magazine; 9, the cartridge-lifter, and 10 the trigger. Cartridges are represented in the magazine in Figs. 1, 2, and 4.

The barrel is screwed securely into the front end of the receiver and moves rearwardly therewith at the recoil, the receiver compressing by means of its arm 11, Fig. 6, the recoil-spring 13 on the rod 12. This rod extends through the arm 11 and the latter slides thereon. In depending lugs on the receiver is fulcrumed the lever 7 on a pin 14, Fig. 7, and consequently said lever moves with the receiver. The upper end of the lever 7 is forked, so as to embrace the firing-pin 5 when the lever extends into an aperture or slot in the lower face of the breech-bolt 4, the said pin having a suitable form to receive the forked end of the lever, as seen in cross-section in Fig. 6. On the lower end of the lever 7 is a lateral lug 15, which occupies a position between two detents or lugs 16 and 17 on the frame, and in the movements of the receiver these lugs or detents act upon the lever to turn it about its fulcrum into different positions. In Fig. 1, which shows the breech closed, the lever 7 is represented with its upper end turned to its extreme position to the front and free from the breech-bolt. This movement is effected by the detent 16 acting on the lug 15 on the lever. The lower face of a lug 18 on the receiver takes over the lever 7 when the latter is in this position, and said lug, together with the detent 16, prevents any movement of the lever in either direction. When the lever is in this position, the

breech-bolt may be withdrawn by hand to permit of cartridges being inserted in the magazine 8. Fig. 5 shows the breech-bolt so withdrawn, the other parts being in the same position as in Fig. 1. The withdrawal of the breech-bolt is effected in the usual way—namely, by drawing out the firing-pin through the medium of its handle 19, the said pin in its turn releasing the breech-bolt by unlocking it. It may be stated here that the breech-bolt is thrown out and in by the lever 7, the momentum of the bolt carrying it at the terminal portions of its movement after the lever shall have disengaged itself. The device whereby the bolt 4 is locked and unlocked is illustrated in Fig. 12. This is a known device and is not claimed herein. It comprises two lever-latches 4^a on the front end of the breech-bolt, having heads adapted to spring 20 into sockets 2^a in the receiver when the breech is closed. When the firing-pin 5 is retracted, shoulder 5^a thereon enters between and wedges apart the opposite ends 5^b of the lever-latches, thus disengaging their heads from the sockets in the receiver and setting the bolt free.

When the gun is fired, the barrel and receiver are driven back by the recoil. The stationary lug or detent 17 then causes the upper end of the lever 7 by acting on the lower end surface 31 thereof to swing over to the rear from the starting position seen in Fig. 1 to the successive positions seen in Figs. 2 and 4. In the position seen in Fig. 2 the forked upper end of the lever 7 has entered the breech-bolt and engaged the firing-pin 5, and by bearing on the shoulder 20 thereon moves the firing-pin rearwardly to its cocking position. This movement of the firing-pin unlocks the breech-bolt and drives the latter to the extreme rear point seen in Fig. 4. When the parts are as seen in this figure, the lever 7 will be swung over to the rear, its face 32, Fig. 9, bearing on the front face of the lug 17, and its face 33, Fig. 9, serving as an abutment or stop for the breech-bolt 4. The spent cartridge-shell drawn out by the extractor (not shown in the drawings) is now ejected and a fresh cartridge supplied. The return of the parts is effected, as usual, by the recoil of the spring 13. This operation again swings the lever 7 over to the front by engagement with the detent-lug 16 in its path, thus closing the breech-bolt. The parts now resume the position seen in Fig. 1.

The magazine forms a part of the receiver 2, and consequently takes part in its movements, thus always occupying the one and the same position with respect to the cartridge-chamber in the barrel. Therefore the feeding up of a cartridge is not dependent on the position of the receiver with relation to the rear part of the firearm, as is the case with automatic firearms as ordinarily constructed and wherein the magazine is stationary in the frame.

When the last cartridge shall have been fired and the breech-bolt thrown forward by the lever 7 at the recoil, said bolt would advance over the cartridge-lifter, as seen in Fig. 3, and interfere with the insertion of cartridges into the magazine. To obviate this disadvantage, the lifter 9 is provided with a spring cushion or buffer, upon which the breech-bolt impinges, and is thereby driven back to the position seen in Fig. 5. This buffer comprises a bolt 21, backed by a spring 22 in a suitable casing on the lifter 9. When the last cartridge shall have been fired, this buffer is brought or elevated into the path of the bolt 4.

The cartridge-lifter 9 is supported on and pressed upward by springs 23, and by means of shoulders on the receiver the movements of the cartridges as they are pressed upward are properly directed in a known manner, so as to bring the uppermost cartridge into alignment with the cartridge-chamber.

As the receding motion of the breech-bolt during the recoil is found to take place later than that of the receiver, means have been provided for retaining the receiver after it shall have completed its rearward movement until the breech-bolt shall have completed its rearward movement. The device employed for this purpose comprises a spring-hook 25, Figs. 11 and 11^a, secured to the rear wall 24, Fig. 3, of the frame 3, a shoulder 26, Fig. 11, formed on the lower face of the lug 18 on the receiver, a sliding pin 27 in the lug 18 forward of said shoulder 26 and projecting into the path of the breech-bolt, and an inclined surface 28 on said bolt. When the receiver shall have receded to the full extent, the shoulder 26 wipes over and engages the depressible hook 25, thus retaining the receiver. The hook 25 presses upward the pin 27 on engaging the shoulder 26. When the breech-bolt shall have receded to the full extent, its cam-like projection 28 wipes over and depresses the pin 27, thus depressing and disengaging the hook 25 and setting free the receiver.

The firing-pin does not unlock the breech-bolt until said pin is withdrawn far enough by the lever 7 to cock, and after the said bolt is set free it remains free until it again advances and closes the breech.

Fig. 11 shows the relations between the trigger and the firing-pin, although this feature is not specifically claimed by us. On the firing-pin is a shoulder 29, which when the pin is drawn back to the cocking position is engaged by a spring latch or sear 30, which has a nose or hook on its pendent end, and when the cocked pin 5 is advanced along with the breech-bolt 4 this nose enters an aperture in a spring-slide 31, engaged by the trigger 10, so that when the trigger is pressed in firing it draws down the slide 31 and with it the sear 30, thus setting free the firing-pin. As this device is not claimed by us and any device

for the purpose may be employed, we have not deemed it advisable to illustrate it in all the views. The mechanism in the receiver is necessarily crowded, and to avoid confusion parts are omitted from some of the views. The cartridge-lifter is omitted from Fig. 11.

Having thus described our invention, we claim—

1. An automatic firearm, having a recoiling receiver, a breech-bolt mounted to slide therein, a firing-pin slidably mounted in said bolt, an operating-lever 7, fulcrumed in said receiver and adapted to engage and operate the breech-bolt positively in closing the latter and to swing out of engagement with said bolt when the latter closes, and a frame having shoulders or lugs for actuating said lever, whereby the breech-bolt, when closed, may be drawn back independently of the operating-lever.

2. An automatic firearm, having a frame provided with actuating-lugs 16 and 17, a recoiling receiver, a breech-bolt slidably mounted therein, and an operating-lever 7, fulcrumed in said receiver, said lever having a lateral lug 15, to engage the lug 16, and a face 32 to engage the lug 17, whereby, when the breech is closed the said lever is held firmly in posi-

tion and cannot rise into engagement with the breech-bolt.

3. An automatic firearm, having a magazine, a cartridge-lifter in said magazine, a spring-buffer on said lifter in the path of the breech-bolt when the magazine is empty, the said breech-bolt, and means for operating the latter.

4. An automatic firearm, having a frame provided with a spring-hook 25, a recoiling receiver in said frame, and provided with a shoulder 26 to engage said hook when the receiver moves rearward from the recoil, and a pin 27 in front of the shoulder 26 and adapted to be protruded by the entering hook 25, a breech-bolt slidably mounted in said receiver and provided with an inclined surface 28, adapted to depress said pin and release the hook 25 when said bolt is moved rearward, and means for operating said bolt.

In witness whereof we have hereunto signed our names in the presence of two subscribing witnesses.
